APPARATUS FOR RECOVERING VOLATILIZABLE METALS

Lloyd Montgomery Pidgeon, Rockcliffe Park, Ontario, Canada, assignor, by mesne assignments, to Dominion Magnesium Limited, Toronto, Ontario, Canada, a corporation of Canada

Application June 4, 1942, Serial No. 445,714
In Canada May 20, 1942

8 Claims. (Cl. 13—8)

This invention relates to a means for extracting volatilizable metals such as magnesium and the like from materials containing the same.

The reactions which occur in the extraction of such metals are usually endothermic and reversible. At any given temperature equilibrium may be readily established, as a result of which the reactions will not proceed in either direction as long as the various reactants, in the equilibrium concentration, remain in the system in which the reactions are carried out. It is thus a necessary step to remove the volatile reaction products from the system continuously and as effectively as possible. In systems heretofore proposed, difficulties have been experienced in carrying out this step in an efficient manner. It is also a necessary step to supply heat to the reaction system to overcome the endothermic reaction, evaporate the metal and heat the charge under treatment to the reaction temperature. Since the charge is usually a poor conductor of heat, it is difficult to achieve this. The temperature of reaction is high and if the charge comes in contact with the heating elements, employed to supply the heat, reaction therewith will ensue.

It is an object of the present invention to provide an apparatus for producing magnesium metal by thermal reduction and distillation in an efficient manner which is substantially free from operating difficulties and disadvantages.

To this end, the invention contemplates apparatus for carrying out a method including the step of passing a charge of magnesium containing material through an elongated reaction zone, effecting an internal movement of the parts of the charge during its passage through the zone, and heating the charge during such passage to reduce and vapourize the metal therein. Further steps include the heating of the charge without direct contact with the heating elements employed, the passing of an inert gas through the zone to remove metal vapours, the condensing of the vapours outside the reaction zone, and the maintaining of a continuous reaction process in the zone while continuously or intermittently feeding a charge thereto and discharging residue therefrom.

The invention will be described with particular reference to the accompanying drawings in which,

Figure 1 is a sectional elevation of an apparatus in accordance with the invention,

Figure 2 is an elevation of a furnace with a suitable form of heating means,

Figure 3 is a sectional elevation of a furnace

showing an alternative arrangement of heating means.

Figure 4 is a fragmentary view in side elevation of the arrangement shown in Figure 3, and Figure 5 is a sectional elevation of another form of furnace.

Referring to Figure 1 of the drawings, 1 is a rectangular chamber of elongated shape providing a vertically extending reaction zone, or column 1', and having its refractory lining formed, on opposite side walls, into a series of steps, shelves, or baffles 2, the upper surfaces of which are downwardly inclined. It will be observed that the baffles on one side are staggered with respect to those on the other side. The upper inclined surfaces are provided with facings 3 of a material, such as graphite or heat resisting metal, which will be non-reactive to the charge to be treated. Beneath each baffle and located closely adjacent the furnace wall is a radiation heating element 4 of the electrical resistance type.

Means for feeding a charge 5, preferably in briquetted form as shown, of a material containing magnesium or other volatilizable metals comprises a pair of hoppers 6 and 7 having a valve 8 therebetween whereby communication between the hoppers may be closed off when a charge is placed in hopper 6. A feeding worm 9 reciprocates the material from hopper 7 and conveys it to inlet 10 of the furnace.

Means for effecting discharge of the residue of the charge may comprise an outlet 11 at the bottom of the furnace, a conveying worm 12 and a pair of hoppers 13 and 14, with a valve 15 therebetween. Alternatively, the outlet 11 may discharge through a liquid seal which will prevent the escape or admission of gases. A poker 16 may be provided adjacent the discharge end for use in freeing the material should it jam. As shown, the poker may be permanently mounted in the furnace wall, a packing gland 17 being provided to prevent escape of hot gases from the furnace.

Means for providing a continuous flow of an inert gas, such as hydrogen, through the furnace, comprises an inlet pipe 18, having valve-controlled branches 19 leading to the hoppers 13 and 14 to pass the gas in countercurrent to the charge, and an inlet pipe 20, having valve-controlled branches 21, leading to hoppers 6 and 7 to pass inert gas downwardly with the charge.

A condenser 22 communicates with the furnace interior at 23 and has an outlet 24 for the inert gas.

In operation, the briquetted charge consisting of magnesia containing material and ferrosilicon, or other reducing agents which produce non-gaseous oxidation products, is fed to the furnace and the residue discharged therefrom, as illustrated, in a continuous manner, the double feed and discharge hoppers constituting gas locks for the system. It will be observed that the briquettes, in their passage through the elongated reaction zone of the furnace, fall from one inclined shelf or baffle to another on the opposite wall, following a substantially zig-zag passage in which a rolling or mixing action is imparted to them, to cause repeated change in the portion of the charge exposed to direct heat radiation from the heating elements. This action substantially eliminates the possibility of localized overheating of any portion of the charge by the heating elements 4. The location of the latter adjacent the furnace wall away from the baffle edges also contributes to the avoidance of local overheating and to the protection of the elements from breakage since there is substantially no possibility of the briquettes coming into contact with them.

An inert gas, such as hydrogen, is passed upwardly through the reaction zone in a countercurrent to the movement of the heated charge, and, owing to the rolling movement of the briquettes, an effective scouring of the reaction mixture is achieved, the metal vapours being swept into the condenser as they are formed. The downward flow of gas into the relatively cool portion of the charge prevents the rise therein of metal vapours. The distillate is indicated at 43 in the condenser.

The furnace may be operated at atmospheric pressure or under vacuum.

The elements 4 may extend through the furnace wall and be connected in series by the circuit 21, as shown in Figure 2.

An alternative manner of arranging the heating elements is illustrated in Figures 3 and 4. As shown, a row of elements 22 have only the end 23 of the top element and the end 24 of the bottom element extending through the wall of the furnace for connection to an electrical circuit 29, the other ends of elements being supported by columns 25 consisting of a series of blocks or bars positioned in recesses 26 in the furnace wall. The ends of the column consist of refractory supporting bars 38 and the remaining portion of each column consists of alternate bars 27 and 28 of a refractory material and a current-conducting material, such as graphite, respectively. It will thus be observed that current flows through one element 22, and the conducting bar 28 to the next element and thus throughout the furnace. One end of each column is resiliently supported by means of a spring 30 seated in a recessed casing 31 in the furnace wall, whereby the columns may be conveniently assembled and disassembled.

In Figure 5, there is illustrated a modification of the furnace shown in Figure 1 comprising a substantially cylindrical furnace 21 having annular baffles 33 and annular heating elements 34 arranged beneath the baffles therein. The baffles have a facing 35 of non-reactive material thereon. The inlet 36 and outlet 37 of the furnace may be provided with suitable feeding and discharge means.

It will be apparent that various other forms of furnace structures may be employed without departing from the spirit of the present invention. For instance, a spiral baffle formation may

alternatively be employed in the cylindrical furnace shown in Figure 5.

Moreover, various other details of the structures described and illustrated may be altered while remaining within the scope of the invention. While the invention has been described with particular reference to the production of magnesium, it may be used for producing other volatilizable metals such as zinc and cadmium.

I claim:

1. Apparatus for extracting volatilizable metals from materials containing them comprising a furnace having an elongated vertically extending reaction zone therein, means for admitting materials to be treated at the top of said zone, a plurality of baffles carried by the furnace wall and extending into said zone, said baffles having inclined upper surfaces adapted to receive materials passing through the zone and to direct the same downwardly, and an exposed heating element located under each of said baffles out of contact with said materials, said materials during their passage through said zone receiving direct radiant heat from said elements, and said baffles imparting a rolling action to said materials to constantly change the surface thereof exposed to said radiant heat.

2. Apparatus for extracting volatilizable metals from materials containing them comprising a furnace having an elongated vertically extending reaction zone, means for admitting materials to be treated at the top of said zone, said materials being adapted to pass by gravity through the zone, baffles carried by the furnace wall and extending into the path of materials in the zone, said baffles having inclined upper surfaces adapted to direct the materials downwardly, exposed heating elements beneath said baffles and lying outside the path of travel of the materials, said materials during their passage through said zone receiving direct radiant heat from said elements, and said baffles imparting a rolling action to said materials to constantly change the surface thereof exposed to said radiant heat, means for discharging residue from the bottom of said zone, and means for providing a continuous flow of an inert gas through said zone in countercurrent to the direction of travel of the materials.

3. Apparatus for extracting volatilizable metals from materials containing them as defined in claim 2, said baffle upper surfaces having thereon a facing of a material nonreactive to the materials under treatment.

4. Apparatus for extracting volatilizable metals from materials containing them comprising a furnace having an elongated vertically extending reaction zone, means for admitting materials to be treated at the top of said zone, said materials being adapted to pass by gravity through the zone, baffles carried by the furnace wall and extending into the path of travel of materials in the zone, said baffles having inclined upper surfaces adapted to direct the materials downwardly, exposed heating elements beneath the baffles and lying outside said path of travel, said materials during their passage through said zone receiving direct radiant heat from said elements, and said baffles imparting a rolling action to said materials to constantly change the surface thereof exposed to said radiant heat, a condenser outside the reaction zone and having communication therewith, and means for sweeping metallic vapours from said zone to said condenser.

5. Apparatus for extracting magnesium from magnesia containing material by thermal reduc-

tion, comprising a furnace having an elongated vertically extending reaction zone, means for admitting materials to be treated at the top of said zone, said materials being adapted to pass by gravity through the zone, a series of baffles on each of two opposed walls of said furnace and each extending into the path of travel of materials in the zone, the baffles on one wall being in staggered relation to the baffles on the opposing wall, each baffle having an inclined upper surface adapted to direct the materials downwardly, and an exposed electrical resistance heating element extending beneath each baffle and lying outside the path of travel of the materials, said materials during their passage through said zone receiving direct radiant heat from said elements, and said baffles imparting a rolling action to said materials to constantly change the surface thereof exposed to said radiant heat.

6. Apparatus for extracting volatilizable metals from materials containing them as defined in claim 5, wherein the ends of said heating elements extend through the furnace wall and including an electrical circuit connecting said ends in series.

7. Apparatus for extracting volatilizable met-

als from materials containing them as defined in claim 5, including a pair of columns in said furnace engaging and supporting the ends of said heating elements, said columns consisting of alternate bars of electrical conducting and non-conducting materials.

8. Apparatus for extracting volatilizable metals from materials containing them comprising a furnace having an elongated substantially cylindrical reaction zone therein, means for admitting materials to be treated at the top of said zone, said materials being adapted to pass by gravity through the zone, a series of annular baffles carried by the furnace wall and extending into the path of travel of materials in the zone, said baffles having inclined upper surfaces adapted to direct the materials downwardly, and an exposed annular heating element located beneath each baffle and lying outside the path of travel of the materials, said materials during their passage through said zone receiving direct radiant heat from said elements, and said baffles imparting a rolling action to said materials to constantly change the surface thereof exposed to said radiant heat.

LLOYD MONTGOMERY PIDGEON.
